UNITED STATES PATENT OFFICE

BENJAMIN H. HERBSTER, OF MILWAUKEE, WISCONSIN, ASSIGNOR, BY MESNE ASSIGNMENTS, TO CHAPLINE-MAYER SHOE COMPANY, OF MILWAUKEE, WISCONSIN, A CORPORATION OF DELAWARE

METHOD OF FORMING BACK HEEL SEAMS FOR FOOTWEAR

Application filed September 24, 1927. Serial No. 221,734.

This invention relates to improvements in method of forming back heel seams for footwear.

Heretofore, shoe manufacturers have encountered difficulties in forming the back heel seam on shoes. The method formerly employed was to stitch the two quarters of leather together on the wrong side, apply a strip of adhesive tape thereto, and then turn the product right side out. This method was fairly successful where a double row of stitching was used, but double stitching is objectionable because the seam formed thereby is not neat in appearance. When the aforementioned method was used with a single row of stitching, difficulties were encountered. After turning the product right side out, there was a pronounced bulging on one side of the seam, and the strip of tape on the inside would wrinkle. The result was a cumbersome looking seam and a poorly shaped heel portion. For these reasons, it became very desirable to devise a new method for taping and smoothing out the seam.

It is one of the objects of the present invention to provide a method of forming back heel seams for footwear which will produce a well shaped back heel portion of the shoe, and a seam which is neat in appearance.

It is a further object of this invention to provide a method of forming back heel seams for footwear in which a single row of stitching is employed.

It is a further object of this invention to provide a method of applying the strip of adhesive tape to the inside of the seam and for smoothing out the seam and shaping the heel portion when the quarters of leather are right side out or in their natural position.

A further object of this invention is to provide a method of forming back heel seams for shoes which is simple, effective, and well adapted for the purpose described.

With the above and other objects in view, the invention consists of the improved method of forming back heel seams for shoes and all its parts and combinations as set forth in the claims, and all equivalents thereof.

The method may be carried out by employing in the practice thereof a machine

such as is shown in the accompanying drawings. In these drawings, in which the same reference characters designate the same parts in all of the views:

Fig. 1 is a side elevation of the improved apparatus for forming the back heel seam for shoes, showing the device in attachment with a portion of a table;

Fig. 2 is an end view thereof;

Fig. 3 is a view of the opposite side of the machine from that shown in Fig. 1, parts being broken away and parts being shown in section;

Fig. 4 is a sectional view taken on line 4—4 of Fig. 3;

Fig. 5 is a sectional view taken on line 5—5 of Fig. 3;

Fig. 6 is a detail view of the front end of the machine, showing shoe quarters in position on the machine, parts being broken away;

Fig. 7 is a side view of a portion of the machine, showing the shoe quarters in position, parts being broken away and parts being shown in section;

Fig. 8 is a view of the inside of the finished product showing the attached strip of adhesive tape; and

Fig. 9 is an outside view of the finished product.

Referring to the drawing, the numeral 12 designates a base member which is arranged to be secured to a table 13. The base member is formed with a right angular arm 14 and a tubular extension 15. Within the tubular extension a bifurcated bearing 16 is slidably positioned. An adjusting screw 19 holds the bearing at any desired length within the tubular extension. Loosely mounted on a pin 18 and within the bifurcated end portion of the bearing is a back heel seam supporting member preferably in the form of a wheel 19. Secured to the tubular extension 15 and having its upper end adjacent the wheel 19 is a tape guide 20 having an eye 21. The upper portion of the arm 14 forms a bearing for the shaft 22. On the outer end of this shaft is a rigidly mounted outer pulley 23 and a rigidly mounted inner pulley 24. On an intermediate portion of the shaft 22 is a tightly fitting

eccentric sleeve 25. Loosely mounted on the eccentric sleeve is an outer collar 26 formed with a downwardly extending arm 27 having a vertically extending slot 28. A bolt 29 projects through this slot and into a bracket 30 which is secured to the arm 14. A spring member 31 held between pins 32 holds the arm 27 yieldingly in a raised position. Secured to and projecting from the lower portion of the arm 27 is a seam smoothing member 33 having an engaging head 34. The front end of the shaft 22 is formed with an eccentric portion 35 which is smaller in diameter than the main part of the shaft and which is positioned off the center of the shaft 22. Journaled on this eccentric portion is a feeding arm 36 having a vertical slot 37. A bolt 38 extends through this slot and into the arm 14. On the lower end of the feeding arm 36, and adjustably positioned within a bore is an inverted T-shaped feeding member 39 having a groove 40 in its lower surface. A set screw 41 is arranged to adjust the feeding member 39 within the bore. Extending downwardly from a bracket 42 on the arm 14 is a guide finger 43. A spring 44 surrounding the upper portion of the finger and position between extensions 45 holds the finger yieldingly in position.

30 The outer pulley 23 is rotated by means of a belt 46 which is connected with driving mechanism 47. The inner pulley 24 is connected by an endless belt with a lower pulley 48. The lower pulley is rigidly mounted on 35 one end of a shaft 49 which is journaled in bearings 50, the latter being secured to the lower side of the table 13. On the other end of the shaft 49 a cranked arm 51 is rigidly mounted. A bearing 52 also secured to the 40 underside of the table has journaled therein a shaft 53, upon one end of which a tape holding wheel 54 is mounted. The wheel 54 is arranged to hold a roll of adhesive tape 55 which is fed to the machine.

45 The operation of the device is as follows: When the power is turned on, the driving mechanism 47 is set in motion and this is transmitted by the belt 46 and the pulley 23 to the shaft 22. As the shaft revolves, a reciprocal motion is imparted to the eccentrically mounted arm 27 and the leather smoothing member 33. A similar motion is given to the arm 36 by the eccentric 35. When the shaft 22 is rotating, motion is also transmitted by the pulleys 24 and 48 to the shaft 49. This causes the cranked arm 51 to rotate and pull the adhesive tape off of the roll, as illustrated in Fig. 2.

To form the back heel seam, the following 60 method is used: Two pieces of leather forming the quarters of a shoe are stitched together on the wrong side. They are then turned right side out, and placed in the machine on the wheel 19, as shown in Figs. 6 and 7. The guide finger 43 rests in the seam.

Adhesive tape which passes from the roll over the cranked arm 51 and through the eye 21 in the tape guide 20, is in place on the wheel 19 with its adhering side up. As the leather is fed in, the feed member 39 goes through the various positions shown by the dotted lines in Fig. 6, pressing down upon and smoothing out the seam and causing the adhesive tape to become affixed to the under side of the seam. The feeding member 39 also tends to push or feed the leather further along the wheel 19. The groove 40 in the feeding member is for the purpose of receiving the seam, as illustrated in Fig. 7. After the strips of leather have passed the feeding member, they are engaged by the head 34 of the smoothing member 33. This member presses upon and smoothes out the seam and shapes the heel portion of the shoe. The finished products 56 are discharged from the machine, as shown in Fig. 6, and it is then necessary to cut off the projecting strips of tape. By this method, a neat seam and a well shaped back heel portion of the shoe are produced, as illustrated in Fig. 9. The 90 smoothing out of the seam and taping are both done while the leather is right side out, so the necessity of turning the leather over, and the consequent bulging, is eliminated. The strip of adhesive tape is also affixed to the inner portion in such a manner that there are no wrinkles, as is illustrated in Fig. 8.

From the foregoing description, it may be seen that the improved method of producing back heel seams for shoes is simple, effective, and well adapted for the purpose described.

What I claim as my invention is:

1. The method of forming back heel seams for footwear which consists in sewing a pair of shoe quarters together while turned inside out, turning the quarters right side out, subjecting the seam on the turned right side of the leather to the action of a smoothing device, and applying to and causing the adherence of a strip of material over the seam on the inside of the quarters.

2. The method of forming back heel seams for footwear which consists in sewing a pair of shoe quarters together while turned inside out, turning the quarters right side out, subjecting the seam on the turned right side of the leather to the action of a smoothing device, and simultaneously applying to and causing the adherence of a strip of material over the seam on the inside of the quarters.

3. The method of forming back heel seams for footwear which consists in sewing a pair of shoe quarters together while turned inside out with a single row of stitching, turning the quarters right side out, subjecting the seam on the turned right side of the leather to the action of a smoothing device, and applying to and causing the adherence of a strip

of material over the seam on the inside of the quarters.

4. The method of forming back heel seams for footwear which consists in sewing a pair of shoe quarters together while turned inside out with a single row of stitching, turning the quarters right side out, subjecting the seam on the turned right side of the leather to the action of a smoothing device, and simultaneously applying to and causing the adherence of a strip of material over the seam on the inside of the quarters.

5. The method of forming back heel seams for footwear which consists in sewing a pair of shoe quarters together while turned inside out, turning the quarters right side out and subjecting the turned right side of the shoe quarters to the action of a smoothing device.

6. The method of applying an adhesive tape for reinforcing the back seam of shoe quarters, which consists in supporting an adhesive tape on a mandrel, pressing the quarters at the seam flesh side against the tape and moving the work to cause molding of the seam into its final form.

In testimony whereof, I affix my signature.
BENJAMIN H. HERBSTER.
